UNITED STATES PATENT OFFICE.

WALTER H. HIMES, OF PITTSBURGH, PENNSYLVANIA, ASSIGNOR TO WESTINGHOUSE ELECTRIC & MANUFACTURING COMPANY, A CORPORATION OF PENNSYLVANIA.

UTILITY DRIVE.

Application filed February 18, 1925. Serial No. 9,975.

This invention relates to power drives and more particularly to power drives for implements.

One object of the invention, generally 5 stated, is the provision of a power drive for implements that shall be simple and efficient in operation and readily and economically manufactured.

A more specific object of the invention is 10 to provide for the automatic withdrawal of the drive members from a position of use when released by the operator and the retention of the members in a predetermined position when not in use.

15 Another object of the invention is the control of the driving motor by the hand that guides the implement during operation.

A further object of the invention is to effect the reduction of the force tending to 20 retain the driving member in a predetermined position as the drive is moved toward a position of use.

It is also an object of the invention to 25 provide a power drive that will permit the movement of the implements in a plurality of planes and their being disposed in substantially any position.

Other objects of the invention will in part 30 be obvious, and in part appear hereinafter.

35 The invention, accordingly, is disclosed in the embodiment thereof shown in the accompanying drawing and comprises the features of construction, combination of elements and arrangement of parts which will be exemplified in the construction herein- after set forth and the scope of the application of which will be indicated in the claims.

For a full understanding of the nature 40 and objects of the invention, reference should be had to the following detailed description taken in connection with the accompanying drawing, in which;

Figure 1 is a side elevation of a power drive, parts being broken away to show the 45 construction which is in accordance with this invention.

Fig. 2 is a section along the line II—II of Fig. 1 showing a train of gears that may be used in the power drive.

50 Fig. 3 is a side elevation of a modified form of the power drive.

Fig. 4 is a view of a modification of the drive shaft showing a construction with rigid and flexible sections.

55 Figs. 5 and 6 are side views of implements

that may be attached to the power drive for operation.

Fig. 7 is a front elevation of the mounting shown in Fig. 1.

Referring now to the drawing, 10 designates the motor of the power drive. As will be readily understood, motors of many different types may be used and the selection, to some extent, will depend on the work to be performed.

60 In the interest of efficiency in power transmission, it is desirable that the drive be adapted to permit the use of a straight drive shaft between the motor and the various implements. In order to provide for proper 70 manipulation of the different implements when a straight shaft is used, the motor is mounted for movement in substantially every direction. However, it is to be understood that while a straight, rigid shaft is 75 desirable, a flexible shaft or a drive shaft consisting of rigid and flexible sections may be used successfully.

In the embodiment of the invention 80 shown in Fig. 1, the motor mounting includes a bracket 14 adapted for attachment to the wall 11 in any suitable manner, such, for example, as by the use of screws 15. As will be noted, the bracket 14 is provided with vertically-spaced outwardly-extending 85 arms in which set screws 18 are adjustably mounted in alinement to engage in bearings formed in opposite ends of a slotted block 16. In this manner, the block 16 may be mounted to rotate freely about a vertical 90 axis.

A motor supporting arm 17, which is forked at both ends, is pivotally connected to the block 16 by means of a horizontally-extending pin 19. In attaching the forked 95 end of the arm, the prongs may be placed either inside or outside of the spaced portions of the slotted block. Since the arm 17 is attached to the block 16 in a manner to permit its oscillation about the axis of the pin 19, the arm may be moved freely in a plurality of vertical and horizontal planes.

In order to retain the arm 17 in a raised position out of the way of an operator, an extensible spring 22 is connected between a 105 pin 23 extending through the block 16 and another pin 21 extending between depending lugs 20 provided on the prongs of the forked end of the arm 17. As shown in Fig. 1, when the spring 22 is contracted, it re- 110

tains the arm in the position indicated by dotted lines.

It will be observed that the lugs 20 are located near the end of the arm and that when the arm is drawn downward to the position shown in full lines (Fig. 1), the pins 21, 19 and 23 are located nearly in alinement. Consequently, the arm 17 may be retained in its lower position by the exertion of a force small in comparison with the pull of the spring 22.

A depending gear and shaft casing 26 is suspended from the motor casing, as shown in Fig. 1. Rotatably mounted in the shaft casing is a shaft 25 connected to the motor shaft 24 by a train of gears 27. It will be readily understood that any suitable train of gears may be used to connect the shaft 25 to the motor shaft.

20 In this particular construction, an internal gear 28 is attached to the motor shaft 24 and meshes with a plurality of gear wheels 29 rotatably mounted on a frame 30 fixed to the gear casing. The gear wheels 25 29 mesh with a gear wheel 31 attached to the upper end of the shaft 25, thereby establishing a connection between the motor shaft 24 and the shaft 25.

30 In order to permit oscillation of the shaft 25 to facilitate the manipulation of the implements, the motor 10 is disposed in gimbal rings, shown generally at 32. The forked end 33 of the arm 17 constitutes the outside member of the gimbal ring mounting provided for the motor.

35 The other member of the gimbal ring mounting, a ring 34, is pivotally mounted between the arms of the forked end 33. Pins 35 are mounted in the ring 34 and disposed along a line extending at right-angles to, and intersecting the pivotal axis of the ring. These pins engage in bearings provided in the motor casing.

40 In this manner, the motor is mounted to permit oscillation of the shaft 25 in a plurality of planes. Since the arm 17 may be moved freely in a plurality of horizontal and vertical planes and the shaft 25 oscillated in every direction, implements attached to the shaft in any suitable manner may be manipulated to operate in many different positions.

45 Implements, such as the brush 36 and beater 37, shown in Figs. 5 and 6, respectively, may be attached to the shaft 25 in any suitable manner, such, for example, as by threading the lower end of the shaft 25 and providing in each implement a threaded opening for the reception of the threaded end of the shaft. In order to prevent the shaft from becoming disengaged from an implement during operation, if a threaded connection is provided, the shaft may be threaded opposite to the direction of rotation during operation.

As shown in Figs. 1 and 4, a hand piece 38 is mounted on the shaft casing, thereby providing means for the manipulation of the implements. Since, in the operation of a device of this kind, it is desirable that the operator have one hand free to hold or move articles to be operated upon, a switch 39 for controlling the operation of the motor 10 is disposed in the hand piece in a convenient place to permit its operation by the hand that guides the implement.

When a beater is used for mixing a batter or the like, a control switch, disposed for operation at will, permits the immersion of the beater before the motor is set in operation. In this manner, the splashing of batters and other mixtures is prevented.

50 In case the power drive is to be used for the performance of polishing operations or the like, in which the implement in use is held in one particular position for a considerable period of time, it is desirable that some means be provided for locking the switch 39 closed. Accordingly, a band 40, disposed to fit over the switch 39 to lock it closed, is slidably mounted on the hand-piece 38.

55 The supply of electric energy to the motor 10 may be effected by the use of flexible conductors 13 connected to any suitable source 95 of supply. In order to support the conductors out of the way of the operator, they may be attached to the arm 17.

60 In some cases, the movement of the motor 10, permitted by the mounting described, is 100 insufficient to meet all requirements and a modification, such as shown in Fig. 3, is provided. As will be observed, this modification includes a carriage 41 attached to the bracket 14 by means of a plurality of 105 bolts 42.

65 A track, adapted to receive the carriage 41, is attached to the wall 11 by means of screws 15. It will be readily understood that the track may be disposed so as to permit the projection of the carriage onto it from either end. When the carriage is mounted on the track, it may be moved to any desired position, thereby increasing the range of movement of the implements. The other parts of the device are the same as those shown in Fig. 1 and it is therefore believed unnecessary to repeat their description in connection with this figure of the drawings.

70 A rigid shaft is sometimes found to be unsatisfactory in performing difficult operations, such as the cleaning of inaccessible parts of containers. Accordingly, a flexible shaft 45, such as shown in Fig. 4, may be 125 provided and adapted for attachment to the shaft 25 in the same manner as the implements. The end of the flexible shaft 45 is adapted for the reception of implements in the same manner as the shaft 25. When a 130

flexible shaft of this type is provided, a bracket 46 may be used for maintaining the shaft 25 in a vertical position, as shown in Fig. 4.

5 In operation, the selected implement is attached to the shaft 25. Then the operator grips the hand-piece 38 and draws the motor downward to the desired position.

It will be observed that as the arm 17 10 moves downward from a horizontal position, the axis of the pin 21 travels toward a line through the pins 19 and 23. Consequently, the effect of the spring 22 gradually decreases until the motor reaches its 15 final position. Thus, the force required to retain the motor in a position for use is small.

After the implement has been set in position for operation, the motor switch 39 is 20 closed by the hand gripping the hand-piece and the implement set in operation. The provision of a manually operable switch in the hand-piece facilitates the control of the implement.

25 It will be readily understood that the implements may be driven at any desired speed by the selection of the proper train of gears. In order to meet certain requirements, a train of gears provided with a gear shift for 30 varying the speed might be introduced. However, for ordinary purposes, a single train of reduction gears may be used.

The construction shown in Fig. 3 is usually provided where it is desired to operate at 35 different places on a table or bench on which it is inconvenient to move the articles to be operated upon. When a construction of this type is provided, the carriage 41 may be shifted along the track 43 to first position 40 the motor and then the drive may be operated in the manner described above.

When the operator has finished with the 45 implement, he releases the hand piece and the spring switch 39 functions to interrupt the motor circuit. The spring 22 raises the arm 17 and, therefore, the motor 10 to the position shown in dotted lines in Fig. 1 and retains the motor in its raised position out of the way of the operator.

50 When a flexible shaft, such as shown in Fig. 4, is used, the rigid portion of the shaft 25 is fixed in a bracket such as 46. The implement attached to the flexible shaft may then be manipulated as desired.

55 Since certain changes may be made in the above construction and different embodiments of the invention may be made without departing from the scope thereof, it is intended that all matter contained in the above 60 description or shown in the accompanying drawings, shall be interpreted as illustrative and not in a limiting sense.

Having described my invention, what I claim as new and desire to secure by Letters 65 Patent is:

1. In combination, a motor, a track adapted to be attached to any support, a carriage movably mounted on the track, an arm disposed on said carriage to permit oscillation about a plurality of axes, gimbal rings adapted to support said motor carried by 70 said arm, a depending drive shaft connected to the motor and means carried by said drive shaft for receiving kitchen implements. 75

2. In combination, a motor, a track adapted to be attached to any support, a carriage movably mounted on the track, an arm disposed on said carriage to permit oscillation about a plurality of axes, gimbal rings 80 adapted to support said motor carried by said arm, a depending drive shaft connected to the motor and means carried by said drive shaft for receiving kitchen implements, means cooperative with said arm to retain 85 said motor in a raised position when not in use.

3. In combination, a motor, a track adapted to be attached to any support, a carriage movably mounted on the track, an arm disposed on said carriage to permit oscillation 90 about a plurality of axes, gimbal rings adapted to support said motor carried by said arm, a depending drive shaft connected to the motor, means carried by said drive 95 shaft for receiving kitchen implements, and a hand-piece provided on said shaft whereby said implements may be manipulated.

4. In combination, a motor, a track adapted to be attached to any support, a carriage 100 movably mounted on the track, an arm disposed on said carriage to permit oscillation about a plurality of axes, gimbal rings adapted to support said motor carried by said arm, a depending drive shaft connected to the motor, means carried by said drive 105 shaft for receiving kitchen implements, a hand-piece provided on said shaft whereby said implements may be manipulated, and a motor switch disposed for operation by the hand that grips the hand piece.

5. In combination, a motor, a track adapted to be attached to any support, a carriage movably mounted on the track, an arm disposed on said carriage to permit oscillation 115 about a plurality of axes, gimbal rings adapted to support said motor carried by said arm, a depending drive shaft connected to the motor, means carried by said drive shaft for receiving kitchen implements, a 120 hand-piece provided on said shaft whereby said implements may be manipulated, a motor switch disposed for operation by the hand that grips the hand-piece, and means adapted to lock the switch closed. 125

In testimony whereof, I have hereunto subscribed my name this 9th day of February 1925.

WALTER H. HIMES.
